(57) **CLAIM**

The ornamental design for a smart watch with curved body, as shown and described.

DESCRIPTION

FIG. 1 is a top, left side isometric view of our new design for a smart watch with curved body, in a first embodiment. FIG. 2 is a bottom left side isometric view of FIG. 1.

FIG. 3 is a top side plan view of FIG. 1.

FIG. 4 is a bottom side plan view of FIG. 1.

FIG. 5 is a left side elevation view of FIG. 1.

FIG. 6 is a right side elevation view of FIG. 1.

FIG. 7 is a front side elevation view of FIG. 1.

FIG. 8 is a back side elevation view of FIG. 1.

FIG. 9 is an isometric view of FIG. 1 with the bands removed from the body of the device; and,

FIG. 10 is an isometric view of the smart watch with curved body of FIG. 1 with the bands in a clasped position.

The features shown in broken lines in the drawings depict portions of the smart watch with curved body that form no part of the claimed design.
